UNITED STATES PATENT OFFICE.

WILLIAM T. LUCKEY, OF RICHMOND, VIRGINIA.

TROUSERS-PRESS.

1,065,260.

Specification of Letters Patent. Patented June 17, 1913.

Application filed September 13, 1912. Serial No. 720,262.

To all whom it may concern:

Be it known that I, WILLIAM T. LUCKEY, a citizen of the United States, residing at Richmond, in the county of Henrico and 5 State of Virginia, have invented new and useful Improvements in Trouser-Pressers, of which the following is a specification.

This invention relates to trousers pressers and has for its primary object to provide a 10 presser of this character in which the trousers may be held therein so as to sustain the fabric smooth and to produce creases throughout the crease lines of the leg portions thereof.

15 Another object of the invention is the provision of a trousers presser wherein the trousers at both ends thereof will be readily and easily clamped so as to prevent puckering while held within the presser, thus assuring uniform crease lines in the fabric and also which will sustain said fabric smooth whereby the trousers will be neatly pressed and creased.

20 A further object of the invention is the provision of a trousers presser in which a pair of clamping sections are hinged together so that the same may be opened and closed and serve as leaves between which the trousers may be placed so that the same can 25 be readily smoothed on the closing of the sections, the trousers being held smooth through the medium of presser boards for the uniform pressing thereof and also the simultaneous creasing so that on the removal 30 thereof, they will be smoothly creased for further use.

35 A still further object of this invention is the provision of a trousers presser in which the hinged sections thereof will be firmly 40 clamped so as to prevent the accidental opening of the sections when trousers are placed therein for the pressing and creasing thereof.

45 A still further object of the invention is the provision of a trousers presser which is simple in construction, thoroughly reliable, and efficient in its purpose, and inexpensive in manufacture.

50 A still further object of the invention is the provision of a trousers presser wherein the trousers may be neatly pressed without the necessity of the ironing of the same in the ordinary well known manner.

55 With these and other objects in view, the invention consists in the construction, combination, and arrangement of parts as will be hereinafter more fully described, illus-

trated in the accompanying drawings, and pointed out in the claim hereunto appended.

In the drawings:—Figure 1 is a plan view of the trousers presser constructed in accordance with the invention, the sections thereof being shown open and a pair of trousers clamped thereon. Fig. 2 is a similar view showing the removable presser board in position on one section and one leg of the trousers folded. Fig. 3 is a side edge elevation of the trousers presser when closed and clamping the trousers therein for the pressing and creasing of the same. Fig. 4 is an end elevation thereof when closed. Fig. 5 is a fragmentary plan view of one of the presser boards. Fig. 6 is a fragmentary vertical sectional view through one section of the presser showing in detail one of the clamps detachably mounted therein. Fig. 7 is a fragmentary vertical sectional view through one of the presser boards. Fig. 8 is a similar view showing a slight modification thereof. Fig. 9 is a fragmentary vertical transverse sectional view through the presser showing one of the latches.

Similar reference characters indicate corresponding parts throughout the several views in the drawings.

Referring to the drawings by numerals, 85 the trousers presser comprises a pair of similarly shaped board-like sections 10 and 11, respectively, the same being swingingly connected at adjacent edges by means of hinges 12 so that the sections may be swung to open 90 or closed position with respect to each other. Each of said sections 10 and 11 is provided with a suitable cloth covering 13, and adapted to be laid longitudinally upon the inner covered faces of the said sections is a pair 95 of trousers A to be pressed and creased, the sections being open and disposed in the same plane with each other to allow the said trousers to be superimposed thereon in a manner shown in Fig. 1 of the drawings. 100 Detachably mounted upon the outer end edge of the section 11 is a pair of spaced clamping members each comprising a base 14 formed at its outer end with a hook 15 which detachably engages the outer free 105 edge of the said section 11, while the inner end of the said base forms a stationary jaw 16, and pivotally connected to this base is a movable clamping jaw 17 which co-operates with the stationary jaw 16 for clamping 110 therebetween the waist band 18 of the trousers A, the movable jaw 17 being formed

with the finger engaging extension 19 whereby it may be manipulated for releasing the waist band 18 of the trousers when it is desired to remove the same from the presser. It will be apparent that when the 5 waist band 18 of the trousers A is engaged in the clamps, the said trousers will be fastened at the waist line thereof to the section 11, whereby the leg portions of the trousers 10 can be smoothed prior to the closing of the sections of the presser.

Adapted to be removably inserted between the leg portions 20 and 21, respectively, of the trousers, resting upon the section 15 11 is a smoothing board comprising outer plies 22 and an intermediate corrugated ply 23, the same being united in any suitable manner. The smoothing board is provided with a suitable cloth covering 24 20 and is of a shape corresponding to the shape of the section 11 but is cut into one edge to form an inwardly tapering notch 25 to accommodate the crotch of the trousers A so that the inner portions of the legs 20 and 21 25 will lie smooth and the said smoothing board will sustain the same in such condition while the trousers are being pressed.

Removably superimposed upon the trousers A and extending throughout a portion 30 thereof resting upon the section 11 is a second smoothing board 26, the same being constructed correspondingly to the smoothing board hereinbefore described with the exception of the recesses and this board 26 35 has fixed to one side near the longitudinal edges thereof the ends of a flexible cord 27, the same being trained through eyes 28 fixed in the said board and has loosely engaged thereon a plurality of clips 29 which are 40 adapted to detachably engage the cuff 30 at the lower end of the leg 20 so as to hold the latter smooth and prevent bulging or puckering thereof, the leg portion 20 being folded on to the smoothing board 26, as shown 45 in Fig. 2 of the drawings, and is smoothed with the hand so as to remove any roughness or creases therein prior to engaging the clips 29 therewith. Superimposed upon the folded leg portion 20 is a third removable 50 creasing board 31 which is of identical construction and shape with respect to the smoothing board 26 hereinbefore mentioned and thereafter the leg portion 21 is folded over on to the said smoothing board 31, after 55 which the said leg portion is smoothed with the hand so that on swinging the section 10 upwardly and inwardly toward the section 11, the trousers will be clamped between said sections for the pressing and creasing thereof, the board 31 being provided on one 60 side with a flexible cord 32 and clips 33, respectively, which are mounted in an identical manner as are the cord and clips 27 and 29, hereinbefore described so that the clips 65 33 will engage the cuff portion 30 of the leg

21, thereby sustaining the same smooth to prevent and avoid wrinkling thereof when in the presser.

The section 11 has suitably pivoted there-to at the longitudinal side and the outer 70 edge, a plurality of catches or latches 34, each being provided with a series of openings 35 for the engagement therein of keeper lugs 36 fixed in the side and outer end edges of the section 10, it being understood of 75 course that on each longitudinal side edge of the section 11 is mounted a single catch, although any number may be used thereon if desired, while at the outer free edge of the said section 11 is mounted a pair of 80 catches so as to engage with the keeper lugs 36 for the fastening of the sections 10 and 11 closed and in clamping relation to each other, it being seen that any one of the catches 34 can be swung outwardly and 85 downwardly away from the lug 36 so as to permit the convenient opening of the presser or the raising of the section 21 thereof. Surrounding the pivoted end of each catch 34 is a housing 37, the same being suitably 90 fixed with the section 11 and has arranged therein a spring 38 which acts upon the pivoted end of the catch 34 to sustain the same in engaging or disengaging position.

The section 10 may fasten closer or far- 95 ther away from the section 11 by adjustably engaging the lugs 36 in the openings 35 in the catches 34 so that the trousers clamped between the sections will be smoothly pressed and creased without neces- 100 sitating the ironing thereof. The free ends of the catches 34 are slightly outwardly curled, as shown at 39, so as to permit the lugs 36 to pass the same for positive en- 105 gagement in the openings 35 therein for the locking of the sections 10 and 11 in closed position for the clamping, pressing, and creasing of the trousers after the latter have been placed therein in the manner as hereinbefore described.

It is, of course, understood that in lieu 110 of the clips, catches, and other adjunct parts of the presser, any suitable devices may be employed without departing from the spirit of the invention and such as come 115 properly within the scope of the claim hereunto appended.

In Fig. 8, there is shown a slight modification of smoothing board wherein between the outer plies 40 is disposed cork 41 so as 120 to give the requisite resiliency to the board. However, in lieu of the cork 41, another suitable resilient material may be interposed between the outer plies of the board if desired.

It will be noted that the leg portions 20 and 21 of the trousers A when mounted within the presser will be held so as to avoid any possibility of irregular creasing thereof and the said leg portions will be sustained 125 130

taut upon the smoothing board to sustain the same smooth and avoid wrinkling thereof. The presser can be made of a size to fit within a dress suit case or other traveling bag. When the trousers have been clamped between the sections 10 and 11 of the presser, there will be no friction or wear upon the trousers so as to wear smooth the fabric thereof which would necessarily cause the same to appear shiny. The trousers when removed from the presser will be neatly creased and the fabric thereof smooth.

From the foregoing description taken in connection with the accompanying drawings, it is thought that the construction and manner of use of the presser will be clearly understood and, therefore, a more extended explanation has been omitted.

What is claimed is:—

A trousers presser comprising swingingly

connected board-like sections, detachable clamping members mounted upon one of the sections and adapted to engage the waist band of the trousers, removable smoothing boards adapted to be interposed between the folded portions of said trousers and also between the swinging sections, means carried by one of the sections and engageable with the other for locking the said sections in clamping relation to each other, and resiliently held clips carried by a pair of the smoothing boards for engaging the free ends of the said trousers to sustain the same taut and in smooth condition upon the boards.

In testimony whereof I affix my signature in presence of two witnesses.

WILLIAM T. LUCKEY.
